DESIGN.

T. OFFICER.
Hair-Net.

No. 6,118.

Patented Sep. 3, 1872.

UNITED STATES PATENT OFFICE

THOMAS OFFICER, OF BROOKLYN, ASSIGNOR TO ABRAHAM G. JENNINGS
OF NEW YORK, N. Y.

DESIGN FOR HAIR-NET.

Specification forming part of Design No. 6,118, dated September 3, 1872.

Specification describing a new Design for Ladies' Hair-Nets, invented by THOMAS OFFICER, of Brooklyn, county of Kings and State of New York.

The drawing shows a diagram which illustrates my new design.

This invention relates to a new form of pillar or mesh for ladies' hair-nets; and consists in making each pillar of six threads, of which two form a chain and the remaining four a sort of zigzag braid within the chain, producing thus a novel and ornamental form of pillar.

a and *b* in the drawing represent the threads forming the pillar-chains. These two threads are intertwined and connected where they cross each other so as to form loops *c c* between them, the succession of loops forming the chains in the pillars. *d* and *e* are two parallel threads laid over the chain, and held in place thereon by two other threads, *f* and *g*, which are similarly placed under the chain.

At about the middle of each loop *c* each thread *f* is carried up and once around the thread next above, and in the same manner the thread *g* is carried up, over, and around *c*. The loop thus formed by the lower threads *f* and *g* is clearly shown in the drawing. The threads are in the same manner carried down and around the threads *d* *e*, respectively, to hold them in place.

The net of this construction is manufactured on a lace-machine with a proper arrangement of cards, in manner similar to that in which hair-nets are usually made on braiding-machines.

What I claim as new is—

The design for the pillars of a lady's hair-net, as set forth.

THOMAS OFFICER.
